US0D1065290S

(12) **United States Design Patent** (10) **Patent No.:** **US D1,065,290 S**
(45) **Date of Patent:** **** Mar. 4, 2025**

(54) **SURVEILLANCE CAMERA**

(71) Applicant: **CANON MEDICAL SYSTEMS CORPORATION**, Otawara (JP)

(72) Inventor: **Takahiro Yamamoto**, Kanagawa (JP)

(73) Assignee: **Canon Medical Systems Corporation**, Otawara (JP)

(**) Term: **15 Years**

(21) Appl. No.: **29/824,601**

(22) Filed: **Jan. 26, 2022**

(30) **Foreign Application Priority Data**

Sep. 30, 2021 (JP) ..... 2021-021366 D

(51) **LOC (15) Cl.** **16-01**

(52) **U.S. Cl.** **D16/203**

(57) **CLAIM**

The ornamental design for a surveillance camera as shown and described.

DESCRIPTION

FIG. 1 is a perspective view of a surveillance camera showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines in the drawings illustrate portions of the surveillance camera that form no part of the claimed design.

1 Claim, 7 Drawing Sheets
